INCOMBUSTIBLE WALL PANEL JOINT

John T. Gartrell, Douglassville, Pa., assignor to Birdsboro Corporation, Birdsboro, Pa., a corporation of Pennsylvania

Filed Nov. 4, 1959, Ser. No. 850,855

1 Claim. (Cl. 20—4)

The present invention relates to incombustible wall panels for buildings and the like.

A purpose of the invention is to obtain improved fire resistance in joints between one incombustible wall panel and another.

A further purpose is to more rapidly and conveniently make a joint between abutting incombustible wall panels.

A further purpose is to make a stronger joint in incombustible wall panels.

A further purpose is to render a joint in incombustible wall panels more adaptable to the particular conditions, so that it can be established by nails, screws, drive screws, and metallic connectors, without, however, destroying the fire resistance.

Further purposes appear in the specification and in the claim.

In the drawings I have chosen to illustrate a few only of the numerous embodiments in which the invention may appear, selecting the forms shown from the standpoint of convenience in illustration, satisfactory operation and clear demonstration of the principles involved.

FIGURE 1 is a side illustration of an incombustible wall of the invention.

FIGURE 2 is an end illustration of one of the wall panels of FIGURE 1 to enlarged scale.

FIGURE 3 is an enlarged fragmentary section of the wall of FIGURE 1 on the line 3—3.

FIGURE 4 is a fragmentary perspective of the end of one of the wall panels, omitting the spline.

FIGURES 5, 6 and 7 are fragmentary perspectives of splines used in making the joint of FIGURES 1 to 4 inclusive.

FIGURES 8, 9 and 10 are sections similar to FIGURE 3 showing variations.

Describing in illustration but not in limitation and referring to the drawings:

There is a considerable need in building construction for improved incombustible or fire walls which will serve as interior walls and in some cases as exterior walls of buildings and the like. It is important in such construction that the walls be fire resistant for a predetermined time, in some cases for as long as eight hours.

Difficulty has been encountered in making joints in abutting fire wall panels without impairing the fire resistance. It is also important that such walls withstand smoke, and have adequately low heat transmission, and the like.

The present invention is concerned with an improved joint between abutting ends of fire wall panels.

The joint of the present invention is quickly and easily made, under very favorable conditions of installation, and yet it does not impair the fire resistance of the wall, and leaves the wall adequately resistant to heat transmission, sound transmission and the like.

The wall of FIGURE 1 consists of three panels 20, 21 and 22 each of which consists of an incombustible board 23 on each side suitably of cement asbestos board of well known character. The cement asbestos board is joined to a core 24 of incombustible material.

The core of the panel is desirably for example made from expanded perlite plus fibrous material.

By perlite it is intended to indicate a natural volcanic glass which contains a small amount of water in its structure. When perlite is heated to an elevated temperature,

2

such as 1700° F., a cellular annealed structure is formed with closed cells and this is available on the market. This expanded perlite is of such low density that it usually floats on water.

5 The expanded perlite is preferably of fine size, suitably through 20 mesh and more desirably through 30 mesh per linear inch.

The expanded perlite is suitably formed into a core material by mixing with from 30 to 90% by weight of a fibrous material such as glass wool, rock wool, slag wool, asbestos or fibrous wollastonite. In the preferred embodiment about 30% by weight of the fibrous material is used.

10 The mixture desirably also will incorporate a small amount, of the order of 1%, of a size or binder such as rosin size.

In some cases much less desirably organic fiber such as sugar cane fiber, cotton fiber, or the like, will be incorporated instead of inorganic fiber, and it does not seriously 15 interfere with the fire resistance because it is very slow burning.

In some cases Portland cement is used as a binder of perlite, in the proportions of 1 cement to 4 or 8 of perlite by volume.

20 The core material will have a density of the order of 11 pounds per cubic foot, a linear expansion between 50% and 97% relative humidity lengthwise of 0.2% and crosswise of 0.09%, a compression resistance of 175 p.s.i., and a sound transmission average attenuation of 38.1 decibels.

25 The thermal conductivity (*k* factor, that is, rate of heat flow through 1 inch thickness of a single kind of material), is 0.34 B.t.u./sq. ft./hr./° F. The thermal expansion from 0° to 75° F. is 0.145% increase.

The water absorption in percent by volume on 2 hours' 30 total immersion is 0.60%.

35 The heat transmission value (*U*, that is, the rate of heat flow through a combination of materials forming the wall in a total thickness of 2 1/4 inches with a core thickness of 2 inches) is 0.148 B.t.u./sq. ft./hr./° F.

40 The incombustible boards 23 are joined to the core at 25 by suitable adhesive such as chlorinated rubber and the core is provided in two sheets suitably joined as by the same adhesive at 26.

45 At the end of each one of the panels, there is a slot 27 which abuts a similar slot in the abutting panel so as to receive an incombustible spline 28 suitably made of cement asbestos board.

50 Each of the slots 27 extends across the full width of the core material 24 at the outer end to provide parallel sides 30, and when it has extended back for a short distance, suitably an inch or more, the slot has converging substantially equilateral sides 31 on the core 24 which extend at an acute angle with respect to each other, and before the two converging sides join proximate to a transverse midpoint of the core, the slot ends in flat base 32.

55 The spline 28 is generally of diamond cross section and has parallel sides 33 at the center which engage the boards at 30, and then converging portions 35 which engage the converging walls 31 of the slot and a flattened end 36 which seats against the flattened end 32 of the slot.

60 Adhesive is applied to the outer surfaces of the spline at 33, 35 and 36. There is an elongated line of adhesive contact with the walls of the slot 31 as compared with a rectangular slot all of whose sides are parallel so that greatly increased bond is obtained when one panel and the next is joined. The adhesive used is chlorinated rubber.

65 When the spline is properly seated in the slots so that the adhesive is in firm engagement, the spline is anchored and the wall panels are locked in place by metallic fasteners which may be nails 37 driven in through the boards 23 from each side of each panel as in FIGURE 3,

care being taken that the nails are not long enough to bring their points close to one another, the nails being substantially shorter than half the thickness of the wall panel, so as to leave space at 38 between the inner ends as shown in FIGURE 3 which is at least a half inch and preferably one inch between the adjoining points of the nails.

The spline has at the center on each side a slot 40 which suitably runs the full length from top to bottom and assists in lining up the center of the spline with the joint 41 between the panels, thus aiding the workman when bringing the panels together in knowing when the spline is fully seated.

The spline is conveniently made in several short pieces 28', 28² and 28³ as shown in FIGURES 5 to 7, the spline 28' being suitably at the top and having a bottom groove 42 across the middle of the lower end. The next spline section 28² has a transverse tongue 43 at the top which interlocks with the groove 42, and a transverse groove 44 at the bottom which interlocks with a transverse tongue 45 on the top of the spline section 28³.

In some cases it is preferred to secure the panels to the spline by wood screws 37' entering from each side of each panel as shown in FIGURE 8, being careful that the wood screws do not intersect and of course extend less than half across the thickness preferably leaving at least a half inch and preferably one inch between their inner ends.

In some cases it is preferred to use drive screws, and in FIGURE 9 I show drive screws 37² extending on one side from each of the panels less than half of the distance across the thickness (desirably with a space of one half inch and preferably one inch from the inner end of the screws on the other side), at the other side screws 37³ anchor a metallic sealing strip which extends across the joint between the panels, and runs lengthwise of the joint.

In FIGURE 10 drive screws 37² enter into the spline from each side of each panel to a distance less than half of the thickness, with a clearance of at least one half inch, and preferably one inch between inner ends, and then an additional sealing strip 37⁵ and 37⁶ on the opposite sides is held by screws 37⁷ which extend in only a relatively short distance compared to the drive screws 37².

All of the metallic fastenings are suitably of steel or stainless steel.

It will be evident that the groove for the spline will suitably be prefabricated at the factory and the spline will be prefabricated so that the joint can be made without requiring cutting on the job. It will also be evident that if the height of the panel is cut down a similar height can be cut off the spline to make it conform with the height of the panel.

In view of my invention and disclosure, variations and modifications to meet individual whim or particular need will doubtless become evident to others skilled in the art, to obtain all or part of the benefits of my invention without copying the structure shown, and I, therefore, claim all such insofar as they fall within the reasonable spirit and scope of my claim.

Having thus described my invention what I claim as new and desire to secure by Letters Patent is:

In an incombustible wall panel joint, a first wall panel of incombustible material having incombustible side boards having a high resistance to heat transmission extending in flat planes and an incombustible core joined to the side boards, there being a slot at the end of the first wall panel which in cross section extends in major width directly along the inside of the side boards from said end and thence extends into the core and has opposite converging substantially equilateral sides extending inwardly of the panel at an acute angle with respect to each other and terminating proximate to a transverse midpoint of the core with a flat base, said equilateral sides and base being formed by the core, a second wall panel abutting the first adjacent to said slot, composed of incombustible material and having incombustible second side boards having a high resistance to heat transmission extending in flat planes at the sides and an incombustible second core joined to the side boards of said second panel between said second side boards, there being a slot in said second panel at said abutting end thereof which in cross section extends in major width directly along the insides of said second side boards from said end of the second panel and thence extends into said second core and has opposite converging substantially equilateral sides extending inwardly of the second panel at an acute angle with respect to each other and terminating proximate to a transverse midpoint of the second core with a flat base, said equilateral sides and base of said slot in said second panel being formed by said second core, a spline of incombustible material having a high resistance to heat transmission and in cross section conforming to the cross section of said slots and thus having opposed parallel flat sides in abutting relationship with said side boards, pairs of opposed sides abutting the corresponding opposite sides of the slots of said panels, and flat end faces abutting the corresponding flat bases formed by said core, and metallic fastenings extending through each side board of the wall panels into the spline for a distance less than half the thickness of the spline.
